(57) **CLAIM**

I claim the ornamental design for footwear, as shown and described.

DESCRIPTION

FIG. 1 is a perspective view of footwear, showing my new design;

FIG. 2 is a top view thereof;

FIG. 3 is a bottom view thereof;

FIG. 4 is a side view thereof;

FIG. 5 is an opposite side view thereof;

FIG. 6 is a front view thereof; and,

FIG. 7 is a rear view thereof.

The broken lines in the drawings represent portions of the footwear that form no part of the claim.

1 Claim, 6 Drawing Sheets

FIG. 2

FIG. 3

FIG. 4

FIG. 7

FIG. 6
